(57) **CLAIM**

The ornamental design for a bottle carrier, as shown and described.

DESCRIPTION

FIG. 1 is a rear perspective view of a bottle carrier according to our new and ornamental design, with a strap of the bottle carrier shown in a first position;

FIG. 2 is a rear perspective view of the bottle carrier of FIG. 1, with the strap of the bottle carrier shown in a second, alternative position;

FIG. 3 is a rear perspective view of the bottle carrier of FIGS. 1 and 2, with the strap of the bottle carrier shown in a third, alternative position;

FIG. 4 is a front view of the bottle carrier of FIGS. 1-3, with the strap shown in a fourth, alternative position similar to the first position of FIG. 1;

FIG. 5 is a rear view thereof;

FIG. 6 is a left side view thereof;

FIG. 7 is a right side view thereof;

FIG. 8 is a top view thereof;

FIG. 9 is a bottom view thereof;

FIG. 10 is a rear perspective view of an alternative embodiment of a bottle carrier according to our new and ornamental design, with a strap of the bottle carrier shown in the first position of FIG. 1; and,

FIG. 11 is a bottom view of the alternative embodiment of the bottle carrier of FIG. 10, with the strap shown in the
